CLAIM

The ornamental design for an adjustable pressure regulator for irrigation systems, as illustrated shown and described.

DESCRIPTION

FIG. 1 is an isometric view of an adjustable pressure regulator for irrigation systems;

FIG. 2 is a front elevation view thereof;

FIG. 3 is a rear elevation view thereof;

FIG. 4 is a top plan view thereof; and,

FIG. 5 is a bottom plan view thereof.

The broken lines showing unclaimed portions of the adjustable pressure regulator form no part of the claimed design.
